UNITED STATES PATENT OFFICE.

WILLIAM H. McNUTT, OF NEW YORK, N. Y., ASSIGNOR TO CARRIE EMMA OWEN, OF FRANKLIN, NEW YORK.

VALVED THERMAL DEVICE.

1,108,459.

Specification of Letters Patent. Patented Aug. 25, 1914.

Application filed May 5, 1911. Serial No. 625,351.

To all whom it may concern:

Be it known that I, WILLIAM H. McNUTT, a citizen of the United States, residing at New York, in the county of New York and State of New York, have invented certain new and useful Improvements in Valved Thermal Devices, of which the following is a specification.

This invention relates to valved thermal devices; and it comprises a safety device for use with inflammable fluids comprising a container for inflammable fluid provided with a novel cut-off device especially adapted for use in combination with said container but also useful in other connections, said device comprising a member having a passage therethrough, a closure for said passage inoperative at ordinary temperatures but adapted to be actuated and to close said passage at elevated temperatures, and venting means operative when said passage is so closed; all as more fully herein-after set forth and as claimed.

When inflammable fluids such as gasolene, gas, benzin, naphtha, etc., are conveyed from some source of supply through suitable supply pipes to a place of use, it is highly desirable, in the event of fire occurring near where the fluid is to be employed, that communication with the main supply be cut off; and it is best that this occur automatically. Thus in ordinary gas systems, service pipes lead from the street mains into the building where the gas is to be used, passing through a gas meter usually located within the building and then through other piping to lighting jets, heaters, stoves, and various other gas consuming devices. When fire occurs in a building thus supplied with gas, the piping is frequently disturbed and broken, and unless the supply from the street main is cut off by hand or automatically, gas pours into the building through the broken piping and adds to the conflagration.

There have been many attempts to provide means for automatically cutting off the gas supply in case of fire, and these have usually involved valve means of one kind or another interposed in the piping at some suitable point, preferably in the service pipe on the street side of the meter. Some of these proposed devices comprise a spring controlled valve, normally held open against the tension or pressure of a spring by a com-

bustible member such as a cord which burns apart when in proximity to flame and releases the actuating spring, causing the valve to turn in its seat and close the service pipe. One objection to such devices is that a seated valve which is seldom moved on its seat tends to become locked in position by reason of corrosion between the contacting metallic surfaces, and such a valve may often fail to close when the spring is released by the cord burning apart. Service pipe closures of the automatic plunger valve type having also been proposed, comprising a plunger valve, normally held away from its seat against the pressure of a compressed spring by a fusible member, which is intended upon fusion of such member at a predetermined temperature to be forced by the spring into the valve seat and to close the service pipe. Devices of the latter type, while heretofore imperfect and unsatisfactory in several respects, are of course to be preferred to those in which the valve is normally seated and is intended to close the service pipe by turning on the valve seat. Both of the types of devices described are open to serious objections, however, as heretofore constructed. It frequently happens that when a building is attacked by fire the gas piping may nevertheless remain intact for some time after the commencement of the fire, or even until it ceases. Considerations of safety demand however that communication between the piping in the building and the street main be cut off promptly when fire occurs, without relying on the more or less remote possibility that the piping will be unharmed and that there will be no escape of gas from the main into the building. Consequently it may often happen that after the service pipe has been properly closed by the cut off valve, there remains a body of gas in the piping and in the meter which cannot escape unless there is some break in the piping. As the fire progresses, this confined body of gas becomes very hot and develops considerable pressure in the meter and piping which is often sufficient to burst the meter. It is well known that in many fires, gas meters which are substantially uninjured by any direct contact with flame, are often rendered wholly useless by bursting because of excessive pressures developed as above described. The ordinary gas meter is of rather light construction being in-

tended for use with relatively low pressures; with pressures of a few inches of water for example.

In the present invention the mentioned disadvantages heretofore inherent in devices of this kind are entirely obviated. In the present device means are provided whereby communication between the supply main and the local piping is effectually cut off when the temperature in the vicinity of the device rises above a certain predetermined limit, while further means, operative only after communication with the supply main has been cut off, allows the gas trapped in the meter and local piping to pass off quietly. If the device be caused to operate by the heat of a naked flame in proximity thereto, the gas thus vented is ignited and burns quietly, thus being consumed by the same agency which causes the cut-off to operate, and being thereby rendered harmless. Whether the local piping remains intact or not, there is thus no danger, where the present invention is employed, of the meter or piping bursting.

While I have referred for purposes of illustration to the use of my new device in combination with a gas distributing system, it may of course be employed in other and generally similar systems where inflammable fluids are handled. For example, it may be advantageously inserted between a gasoline supply tank and a carburetor or automobiles or motor boats.

In the accompanying drawings I have shown more or less diagrammatically certain embodiments of the present invention.

In this showing: Figure 1 is a longitudinal cross section of one form of cut-off member; Fig. 2 is an end view of a valve plug; Fig. 3 is a section on the line III—III of Fig. 1, certain parts being removed; Fig. 4 is a longitudinal section of another form of cut-off member; Fig. 5 is a section on the line V—V of Fig. 4; Fig. 6 is an end view of a modified valve plug; Fig. 7 is a detail; Fig. 8 shows the cut-off device applied to a gas meter; and Fig. 9 shows another container provided with the device.

Referring to the drawings, 1 is a fitting or valve casing having a fluid-conducting passage 2 extending therethrough, and suitably connected as at 3 and 4 to piping. Extending transversely of the passage is valve chamber 5, closed at its outer end by screw cap 6. The opposite end of the valve chamber is shaped to form a seat 7 for valve plug 8. Referring now more particularly to Fig. 1, the valve plug is provided with vent channel 9 which may extend inwardly from the side of the plug and then axially thereof to the smaller end, and which opens into hollow stem 10 which in turn extends through end wall 11 of the valve chamber 65 with a sliding fit and terminates in hemi-

spherical valve 12 normally seating on the edge of circular opening 13. This valve prevents fluid from passage (2) entering chamber 14 which is closed by screw cap 15 having vent opening 16 in alignment with hollow stem 10. Located within this second chamber between and sealing the end of the hollow stem and the vent (16) is a plug or block 17 of fusible material such as wax paraffin, low fusing metal, such as various alloys of cadmium, bismuth, tin, lead, etc., or the like, serving at ordinary temperatures to hold the valve on its seat and the valve plug (8) away from its seat against the pressure of compressed spring 18 which may be centered by guide element 19. The pressure of the spring is adjusted by manipulating the screw cap (6). In this type of valve, the fusion of the plug 17 of paraffin or other low melting material releases the spring actuated plunger valve which immediately moves forward to close the fluid passage (2). At the same time, the ball valve (12) leaves its seat and, together with the hollow stem, is pushed forward into contact with the vent (16), the vent and end of the hollow stem being in alignment. The passage (2) is thus completely closed on one side of the valve, while on the other side, which is next the meter, there is communication between the passage and outside of the device, through the L-shaped vent channel, the hollow stem and the vent in the screw cap. Any gas in the meter and local pipe system, which upon heating would otherwise develop bursting pressure, is thus allowed to escape quietly, while flow of gas from the supply main is effectively cut off.

In Fig. 4 is shown a modification of the device of Fig. 1, which is advantageously employed under certain conditions. In Figs. 1 and 4, similar reference characters refer to similar parts. In the modification shown, the plunger valve, instead of having a valve channel extending through its body, is provided with an external groove 20 extending the whole length of the valve on the meter side. Inset in the smaller end of the valve plug are a number of guides 21 for a purpose later described. At the end of the device opposite the spring is a threaded member 22 screwed into the fitting, forming a chamber closed by a screw cap 23 provided with one or more vent openings 24. At the inner end of the member (22) is secured by brazing or welding a disk 25 of brass or other suitable metal having apertures 26 therethrough engaging the ends of the guides before mentioned and having vent orifices 27. Lying against this disk is a second disk 28 of a fusible material such as sealing wax or some similar substance which is not affected by the fluid with which it is to come in contact and which prevents entrance of fluid from the valve chamber into

the chamber containing the fusible plug hereinafter referred to. Between the sealing wax disk and the screw cap is a plug 29 of fusible material which may have centering elements 30 integral therewith. This plug, together with the sealing wax disk normally holds the plunger valve away from its seat against the pressure of the actuating spring. As will be noticed, in this modification, the valve structure (12) shown in Fig. 1 is done away with; while in its place is the sealing wax disk which effectually seals the end of the plunger valve chamber. The guides attached to the valve plug and engaging the orifices in the brass disk prevent the valve from being accidentally turned about its axis. The length of the guides should be such that when the plunger valve is released the ends of the guides do not quite touch the cap (23). A small clearance space 30^a prevents the vent orifices in the brass disk being closed when the plunger valve seats.

When the valve device becomes heated above a predetermined temperature, the fusible plug and sealing wax diaphragm melt and permit the spring to force the valve against its seat, entirely closing passage (2). The vent openings in the screw cap of course permit the material of the fused plug to pass out of the cut-off device, and communication between the lower part of conduit 2 and the outer air is thus established by way of groove (20), orifices (27) and vents (24). At the same time the opening into the upper portion of conduit 2 is closed. In this type of valve there is also communication, when the valve is seated, between the portion of the valve chamber adjacent to the spring and the outer air, which prevents the pocketing of gas in that portion of the valve chamber. The sealing wax disk while melting at approximately the same temperature as the fusible plug, prevents the latter from being dissolved where gasoline or similar liquids are passed through the device. Sealing wax is practically insoluble in such liquids. One type of sealing wax is a calcium resinate, a body insoluble in hydrocarbons, such as gasoline. As before stated, the new cut-off may be used in various combinations. For example, in Fig. 8 it is shown set between a meter 31 and service pipe 32 leading to a street main not shown. Pipe 33 leads to some local piping system, as for example the gas piping in a building. In Fig. 9 the cut-off is shown between a motor boat or auto-

mobile gasoline supply tank 34 and pipe 35 leading to a carburetor. The tank may be provided as shown with venting means 36 to which is best attached a safety tube 37 of metal gauze or screen. When necessary or desirable the vent of the valve device itself may also be protected with a safety tube attachment or other protecting means comprising metal gauze to prevent back-drafting of flame into the meter or other container.

My new automatic cut-off device may also be interposed in the feed pipe of a gasoline tank or other liquid container, with the valve vent turned so as to communicate with the container. A discharge pipe may connect with the valve vent and may lead to some suitable container located at a point more or less remote from the gasoline tank. In the event of fire occurring near the tank, the cut-off device would then operate to permit automatic discharge of the tank contents into the container at a safe distance from the fire.

I claim—

1. A fluid controlling device, comprising a fluid conduit, a valve chamber disposed substantially transversely thereof and having a valve seat, a valve member in said chamber adapted to close said conduit by engaging the valve seat, fusible means normally holding said valve member away from said seat, means in said valve member for venting a limited portion of said conduit when said valve member is seated, and means comprising guide members secured to said valve member to prevent said valve member from turning axially. 95

2. A fluid controlling device, comprising a fluid conduit, a valve chamber disposed substantially transversely thereof and having a valve seat, a valve member in said chamber adapted to close said conduit by engaging the valve seat, fusible means normally holding said valve member away from said seat, means in said valve member for venting a limited portion of said conduit when said valve member is seated, and a disk of material substantially insoluble in hydrocarbons separating said fusible means from said valve chamber. 105

In testimony whereof, I affix my signature in the presence of witnesses.
